UNITED STATES PATENT OFFICE.

HOWARD S. EVANS, OF PITTSBURG, PENNSYLVANIA.

DESIGN FOR A LAMP-SHADE.

41,081.

Specification for Design.

Patented Jan. 10, 1911.

Application filed November 2, 1910. Serial No. 590,411. Term of patent 14 years.

To all whom it may concern:

Be it known that I, HOWARD S. EVANS, a citizen of the United States, residing at Pittsburg, in the county of Allegheny and State of Pennsylvania, have invented a new, original, and ornamental Design for Lamp-Shades, of which the following is a specification, reference being had to the accompanying drawing, forming part thereof.

The figure is a side view of the shade.

I claim:

The ornamental design for lamp shade, as shown.

HOWARD S. EVANS.
